Term of patent 14 years

U.S. Cl. D49—17.1
Int. Cl. D7—06

FIG. 1

FIG. 2

FIG. 4

FIG. 3

FIG. 5

FIG. 6

FIGURE 1 is a front elevational view of a bag for a vacuum cleaner showing our new design;

The dominant features of our design reside in the portions shown in full lines. The texture partially shown in FIGS. 1-4 and FIG. 6 is understood to be continuous over the surface of the bag.

We claim:

The ornamental design for a bag for a vacuum cleaner, substantially as shown and described.
